RATCHETING STUD WRENCH

John Keiser, Windsor, Colo.

Application June 6, 1949, Serial No. 97,448

1 Claim. (Cl. 81—53)

1. This invention relates to a stud bolt wrench.

It is exceedingly difficult to remove cylinder head stud bolts after the latter have become rusted and corroded in place. The principal object of this invention is to provide a simple, light-weight, easily used wrench which will obtain a secure grip upon a stud bolt, and which can be pre-set to rotate the bolt with a ratcheting action in either desired direction.

Another object of the invention is to provide convenient means to enable the operator to set the wrench for either tightening or loosening the stud bolt.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved stud bolt wrench;

Fig. 2 is a top view thereof;

Fig. 3 is a vertical section, taken on the line 3—3, Fig. 2;

Fig. 4 is a horizontal section, taken on the line 4—4, Fig. 3;

Fig. 5 is a similar section, taken on the line 5—5, Fig. 3, illustrating the wrench in place on a typical stud bolt;

Fig. 6 is a detail, side view of a ratcheting dog employed in the improved wrench; and

Fig. 7 is a reduced scale bottom view of the improved stud bolt wrench.

The improved wrench comprises a cup-like housing 10 having a central stud bolt opening 11 in its bottom and closed at its top by means of a removable cap plate 12. A hollow stem 13 extends downwardly through the cap plate 12, terminating in a terminal flange 14 at its lower extremity. The upper extremity of the stem is provided with suitable wrench-engaging faces 15.

The flange 14 rests against a shoulder 16 formed on the interior of the housing 10, and is prevented from moving upwardly by means of a snap ring 17 which is inset in an internal, annular groove in the housing 10. The flange 14 is prevented from rotating, with reference to the housing, by means of outwardly extending ears 32 formed on the flange which rest in receiving sockets 33 formed in the sides of the upper edge

2

of the housing 10. The cap plate 12 is held down on the housing 10 by means of a set collar 18 which is secured to the stem 13 by means of a suitable set screw 19.

Three swinging toothed dogs 20 are positioned within the housing 10 below the flange 14. Each dog is provided at the outer extremity of its bottom surface with a downwardly extending pivot lug 21 which engages in a pivot opening 22 formed in the bottom of the housing 10 adjacent the periphery thereof. The pivot openings are so positioned that when the dogs are swung inwardly on radial lines, they will be spaced equidistant from each other, as shown in Fig. 2.

Each dog is provided with a rounded upstanding boss 23 on its upper surface adjacent its free inner extremity. The opposite faces of the free extremities of the dogs round inwardly to substantially vertical apex edges, and these inwardly rounded faces are provided with vertical gripping teeth 24.

The bosses 23 project upwardly into radial slots 25 formed in a rotatable shifting disc 26. The disc 26 is positioned between the dogs 20 and the flange 17. An eccentrically positioned shifting pin 27 is locked in the top plate 12 by means of a lock nut 28 and extends downwardly therefrom through a circumferential notch 29 in the flange 14 and through a receiving opening in the disc 26.

Thus, it can be seen that, due to the pin 27, the disc 26 will rotate in unison with the top plate 12. The peripheral edge of the top plate 12 is preferably knurled, as illustrated in Fig. 1, to provide a convenient finger grip for rotating the plate.

The plate 26 is constantly urged toward an intermediate position, which will place the axis of the slots 25 in radial alignment with the axis of the dogs 20, as shown in Fig. 2 by means of a pair of tension springs 30. Each of the springs 30 is looped about the pin 27 at its one extremity and extends to a spring stud 31 at its other extremity. The spring studs 31 are mounted in the flange 14.

To place the wrench upon a stud bolt such as indicated at 34, for the purpose of unscrewing the same, the top plate 12 is rotated so as to rotate the disc 26 counter-clockwise sufficiently to swing all of the dogs 20 out of the path of the stud bolt against the tension of one of the springs 30. The wrench is then placed over the bolt 34 and the top plate is released, allowing the tensed spring 30 to pull the right-hand toothed face 24 of each dog against the stud bolt.

The entire housing is now rotated back and forth by means of any suitable wrench placed

upon the wrench-engaging faces 15. As it moves to the right, the teeth will bite into the stud and rotate the latter. As it moves to the left, the teeth will slide to the left over the surface of the stud to the next engaging position.

To unscrew a stud bolt, the plate 12 is rotated in a clock-wise direction so as to swing the dogs 20 to the left to bring the left side of their toothed surfaces against the stud. Back-and-forth rotation of the stem 13 will then act to unscrew the stud.

When the plate 12 is rotated in either direction, one of the springs 30 will be tensioned, while the other will be relieved. The tensioned spring in each case acts to hold its respective toothed face against the stud.

While a specific form of the improvement has been described and illustrated herein, it is to be understood that the same may be varied, within the scope of the appended claim, without departing from the spirit of the invention.

Having thus described the invention, what is claimed and desired secured by Letters Patent is:

A ratcheting stud wrench comprising: a housing; a flange member fixedly mounted in said housing; a stem extending axially from said flange member for rotating said housing; a plurality of eccentric swinging dogs pivotally mounted in said housing and adapted to engage a stud; a radially slotted shifting disc positioned over said dogs and below said flange member, the slots in said shifting disc engaging projections on said dogs to swing the latter in consequence of rotation of said shifting disc; a cap

plate rotatably surrounding said stem and closing the top of said housing; a collar secured to said stem above said cap plate and preventing upward movement of the latter; a shifting pin eccentrically mounted in said cap plate and extending downward therefrom through a circumferentially elongated notch in said flange member and into a receiving opening in said shifting disc for rotating the latter in consequence of rotation of said cap plate; a spring stud extending upward from said flange member at each side of said stem; and a similar tension spring tensioned between each spring stud and said shifting pin and acting to bias the latter at its medial position.
